United States Patent Office

Des. 186,299
Patented Oct. 6, 1959

186,299

TEXTILE FABRIC OR SIMILAR ARTICLE

John J. Daus, Jr., Evansville, Ind., assignor to Anchor Supply Company, Inc., Evansville, Ind., a corporation

Application August 10, 1955, Serial No. 37,400

Term of patent 3½ years

(Cl. D92—1)

The figure is a plan view of a textile fabric showing my new design; a unit is enclosed within the dot and dash lines, which unit is repeated as indicated by the extensions beyond the unit boundaries.

I claim:

The ornamental design for a textile fabric or similar article, as shown.
